[57] CLAIM

The ornamental design for a type font, as shown.

DESCRIPTION

The FIGURE is a face view of a type font, showing my
new design.

A handwritten sample of the type font design, showing a variety of characters including uppercase and lowercase letters, numbers, and punctuation marks. The characters are stylized with unique, rounded, and somewhat irregular shapes, particularly the letters 'A', 'B', 'E', 'F', 'S', 'H', 'I', 'J', 'K', 'L', 'M', 'N', 'U', 'V', 'W', 'X', 'Y', 'Z', 'a', 'b', 'c', 'd', 'e', 'f', 'g', 'h', 'i', 'j', 'k', 'l', 'm', 'n', 'o', 'p', 'q', 'r', 's', 't', 'u', 'v', 'w', 'x', 'y', 'z', and the numbers '1', '2', '3', '4', '5', '6', '7', '8', '9', '0'. Punctuation marks shown include a comma (,), a semicolon (;), a dollar sign (\$), an exclamation point (!), a question mark (?), a brace ({}), and a tilde (~).
